UNITED STATES PATENT OFFICE.

OLIVER P. JOHNSON, OF CAMBRIDGE, MARYLAND.

REFRIGERATING PRESERVING-PACKAGE.

SPECIFICATION forming part of Letters Patent No. 250,150, dated November 29, 1881.

Application filed May 3, 1881. (No model.)

To all whom it may concern:

Be it known that I, OLIVER P. JOHNSON, a citizen of the United States of America, residing at Cambridge, in the county of Dorchester 5 and State of Maryland, have invented certain new and useful Improvements in Refrigerating Preserving-Packages; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 This invention relates to improvements in packages for the preserving and transporting of oysters and other similar perishable articles, said improvements pertaining more especially to packages such as shown in Patent No. 20 240,143, heretofore granted to me.

25 My present object is to provide packers and shippers with a preserving-vessel which shall be more easily and cheaply constructed than those heretofore employed, and which, while necessitating fewer parts, shall, nevertheless, 30 operate to preserve such articles as above indicated for a shorter or longer time by thoroughly protecting them from the action of the air and of heat, especially preventing the passage of these through the upper end of the package during transportation.

Figure 1 is a vertical section of a package embodying some of my improvements. Fig. 2 is a top or plan view. Fig. 3 is a view of a 35 slightly-modified package. Fig. 4 represents another modification, and shows also the combination, with a wooden barrel, of a non-conducting paper packing.

40 In the drawings, A A represent the staves of which the package is formed, and B B hoops whereby they are held together in the ordinary manner. The package is made liquid-tight and of a strength sufficient to meet the demands of transportation. At the upper end 45 the barrel or package is provided with two heads, (or a double head,) as shown at C and D. The inner head, C, is secured in place by means of a croze, in substantially the ordinary manner, and the upper portion, D, is retained by 50 means of the inwardly-turned ends of the staves, the head being beveled to properly cor-

respond to the shape of the staves. Between the heads C and D there is placed a non-conducting packing, E, preferably made of paper. The heads D and C and the packing E are fastened firmly together by means of bolts or screws, so that they shall form a compact head, and shall prevent the transmission of heat. At the center of the head thus constructed there is formed a circular aperture for the insertion 60 and withdrawal of the ice-holder F. The aperture through the inner head, C, may be somewhat less in diameter than that through the outer head, D, as shown in Figs. 1 and 3; or the apertures through the two parts C and D 65 may be of the same diameter, as shown in Fig. 4.

The ice-holder F is preferably constructed as shown—that is to say, with an upwardly-turned flange, g, at the upper end, and with an internal screw-thread, f. Within the top of 70 the holder fits a screw-cap, a. The flange g of the ice-holder rests upon a shoulder, which is either formed in the inner head, C, or formed upon a metallic strengthening-collar inserted through the apertures in the heads. I have 75 shown collars adapted to receive and support the ice-holder, and at the same time strengthen the heads and protect the grain of the wood where it is exposed by forming the central apertures. The collar is cast in form ready to be 80 inserted in its place, and is formed with a flange, G, a vertical part, H, and a lower flange or shoulder, b. It is held in place by means of bolts or screws h h, which may be also utilized to hold together the heads C and D. In Figs. 1 and 85 4 the strengthening-collar extends to the inner face of the inner head, C. In Fig. 3 it is shown as not extending to the inside of the head C, but is arranged to leave the wood in contact with the ice-holder, so that there shall be no 90 metallic connection from the inside to the outside of the package, with the exception of the small screws necessary to clamp the parts.

J represents a cover, adapted to fit within the central aperture above the ice-holder and to hold said holder properly in place. Upon the under side of the cover J there is screwed 95 a non-conducting packing, K, and to the upper side of the cover there is secured a hinging and locking arm, L.

In a patent, No. 240,143, granted to me April 12, 1881, I showed and described an oyster-

package formed of an inner barrel having a head at each end, an outer barrel having a head at each end, and a non-conducting packing between the barrels and between the heads. 5 For many purposes a barrel is desired cheaper than the one shown in the said patent, which, however, shall attain many of the advantages therein set forth.

Many perishable substances can be preserved 10 sufficiently long without the outer barrel, or even the non-conducting packing around the sides, if they can be protected entirely from the air and from the action of heat upon the upper heads. The barrel which I have herein shown 15 will accomplish this purpose, and can be constructed at much less expense than the one heretofore patented.

If desired, double heads may be used at the 20 end of the package opposite to that hereinbefore described, as shown at N and O in Fig. 1; but ordinarily in transportation there is less liability for the contents to be injured, either 25 by air or heat passing through the bottom, the package generally resting upon that end during transportation.

The ice-holder is supported laterally at the lower end by a stud, c, adapted to enter the socket d in the lower end of the ice-holder.

In the aforesaid patent I showed a thin (comparatively) non-conducting packing and an outer barrel. I have found that many of the purposes of my invention can be attained without the outer barrel, if the paper packing be properly secured and prepared. The packing 35 in said patent was formed of superposed layers or folds from a continuous sheet of paper. A packing more efficient under some circumstances can be formed by applying to the outer surface of the wooden barrel a layer of pulp of 40 suitable thickness by any of the processes now well known. The layer thus applied can be painted and otherwise prepared in the usual manner to make it durable without interfering with its non-conducting properties. In 45 Fig. 4, I have shown, at Q, a packing of the character last described. In my aforesaid patent the ice-holder was supported upon one set of staves and the hinged cover for said ice-holder (and for its aperture) was supported upon 50 another set of staves. In my present construction I have so arranged the parts that I can support the ice-holder and its cover by means of a head held in place in a single set of staves, which head is arranged to tightly close the end 55 of the vessel formed by said staves.

Under some circumstances I use, in combination with the non-conducting wrapper or packing Q, the head C D E without the other parts shown and described in detail—that is 60 to say, the head may be made continuous with-

out the central aperture or with an aperture in a different location.

I so place the crozed portion of the head that the outer wrapper shall extend to a point above the head, whereas in the packages heretofore constructed the heads were flush with the outer wrappers, and when no outer wooden barrel is used around the non-conducting wrapper there is less protection when the head is placed thus flush with the end of the wrapper 70 than when it is placed at a point above the wrapper, as herein shown.

What I claim is—

1. In a preserving-package, the combination of the following elements, namely: a vessel 75 formed of the staves A A, the inner head, C, the outer head, D, both supported by the same staves A A, the intermediate packing, E, and the detachable ice-holder F, substantially as set forth.

2. In a preserving-package, the combination 80 of the following elements, namely: a vessel formed of the staves A A, the ice-holder F, situated centrally within said vessel, the cover J of said ice-holder, and a head which is supported entirely within the staves A A, and which supports the ice-holder and the cover, substantially as set forth.

3. As an article of manufacture, the herein-described preserving-package, having the inner wooden vessel formed of staves and hoops, and the paper non-conducting packing Q, formed of a web or layer of pulp placed directly 90 upon the wooden part and afterward dried and hardened thereon, as set forth.

4. In a preserving-package, the combination, with an inner wooden vessel, of a head secured within said vessel near the end, and a paper non-conducting wrapper or packing arranged to extend to a point beyond the head, substantially as set forth.

5. In a preserving-package, the combination, with a wooden head and the detachable ice-holder F, of the metallic collar secured to said head, and provided with a seat for the support 105 of said ice-holder, substantially as set forth.

6. In a preserving-package, the combination, with the wooden inner vessel formed of staves and hoops, and the head of said vessel, of the non-conducting packing E, situated within 110 said vessel and supported by said head, and the outer non-conducting wrapper or packing, Q, placed around and supported upon the outside of said vessel, substantially as set forth.

In testimony whereof I affix my signature in 115 presence of two witnesses.

OLIVER P. JOHNSON.
